US00D970604S

(12) **United States Design Patent** (10) **Patent No.:** **US D970,604 S**
(45) **Date of Patent:** ** *Nov. 22, 2022

(54) **PRINTER**

(71) Applicant: **BROTHER INDUSTRIES, LTD.**,
Nagoya (JP)

(72) Inventor: **Masahide Asano**, Nagoya (JP)

(73) Assignee: **BROTHER INDUSTRIES, LTD.**,
Nagoya (JP)

(*) Notice: This patent is subject to a terminal disclaimer.

(**) Term: **15 Years**

(21) Appl. No.: **29/690,299**

(22) Filed: **May 7, 2019**

(30) **Foreign Application Priority Data**

Nov. 8, 2018 (JP) 2018-024533

(57) **CLAIM**

The ornamental design for a printer, as shown and described.

DESCRIPTION

FIG. 1 is a perspective view of the printer;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof; and,
FIG. 7 is a bottom plan view thereof.
The evenly spaced broken lines depict unclaimed parts of
the printer and form no part of the claimed design.

1 Claim, 7 Drawing Sheets
